MAGNETIC WIRE RECORDING

Terry M. Shrader, Oaklyn, N. J., assignor to Radio Corporation of America, a corporation of Delaware

Application January 31, 1947, Serial No. 725,559

1 Claim. (Cl. 274—4)

1

My present invention relates to improvements in telephones of the type employing magnetic-wire records and has for its principal object to provide an improved reeling system including a wire-record that will not "roll" (about its long axis) in its travel between the reels, whereby the same circumferential section of the wire will always be presented to the sound-head of the recording and/or reproducing machine.

The achievement of the foregoing principal object of my invention permits me to provide longitudinally-magnetized wire-recordings of substantially constant fidelity, and this too without the necessity of employing an apertured pole-piece assembly or other orificed "pick-up" through which the wire must be threaded.

Alternatively, my present invention permits me to magnetize the wire in the transverse direction and thereby to achieve the low recording and play-back speeds heretofore practical only with tape-records. In this connection it will be recalled that previous attempts to achieve a transversely-magnetized-wire recording system have invariably involved the use of a multiplicity of magnetic-pole-pieces arranged in circular array about a common point in the path of the wire and a phase-shifting network or other balancing system for handling the signal-energy picked-up by the several discrete pole-pieces. (That such prior-art systems are impractical will be apparent when one appreciates the degree of precision that would be required to make and to install such a pole-piece assembly about a wire that is only a few thousandths of an inch in diameter.)

The non-rolling wire-record and the reeling system of my invention when applied to a transverse-recording system may employ a single pair of pole-pieces of conventional design.

My invention may be said to be predicated upon an appreciation of the fact that a wire which has been endowed with a circular set (so that, when unrestrained, it will curl-up in the form of a circle of certain dimensions) will resist rolling to a very much greater degree than will the same wire when not set, or straight. I of course appreciate that most any wire will acquire a set when wound upon a supply spool or after repeated excursions about a reeling system or other curved path, but I have ascertained that the nature and orientation of the set thus normally acquired is of no useful significance in solving the problems with which I am concerned. Thus, my invention may be said to reside, at least in part, in discovering the degree and orientation of set required to prevent a wire from roll-

ing and in the application of this discovery to the art of magnetic-wire recording. My invention may be said further to reside in the provision of a reeling system wherein the factors of reel-and-pulley design which tend to cause a moving wire to roll are eliminated and, further, in the provision of a simple, inexpensive and convenient method of endowing an unwound wire, a previously wound wire or a presently-wound wire with the set required to minimize rolling in a reeling system of any particular size or complexity.

My invention will be described in connection with the accompanying drawing wherein:

Fig. 1 is a diagrammatic view of a winding system showing one manner of endowing a previously-wound magnetic-wire with a circular set of the orientation and degree required in the practice of my invention;

Fig. 2 is a view perspective of a reel assembly showing a preferred way of endowing a presently-wound magnetic-wire record-blank with a circular set, in accordance with my invention;

Fig. 3 is an enlarged fragmentary view of one of the pulleys or rollers of Fig. 2 showing the improved conformation of the wire-receiving grooves, as dictated by my present invention;

Fig. 4 is an enlarged elevational view of one form of sound-head which may be utilized in longitudinally-recording signals upon a magnetic wire-record, and

Fig. 5 is a similar view of a sound-head having two oppositely located pole-pieces for magnetizing a non-rolling wire "transversely."

Referring to Fig. 1: In carrying my invention into effect I may impart a circular-set to the magnetic-wire W by running it, preferably under slight tension, around a thin rod, cylinder or roller R. When received from the manufacturer the wire will usually exhibit a spiral set by reason of its being wrapped around and along the core of a shipping spool S. Such a spirally-wound wire will roll while being unwound and I find that if I impart a circular set to the wire while it is subject to rolling, the molecular forces which give rise to this movement will be stored in the wire and cause it to roll at some future time. I find that the rolling movement incident to unwinding the wire from its shipping spool can largely be dissipated by providing guide rollers G¹ and G² on opposite sides of the "setting-roller," or rod R, preferably several feet away from the point at which the wire leaves the spool S. I also make sure that the wire runs over the rollers G¹, R, G² and onto the tele-

graphones storage reel 1 in the same direction that it was originally wound upon its shipping spool S. Thus, as shown in Fig. 1, when the wire is wound counter-clockwise on the spool S, I run it over the said rollers and onto the storage reel 1 in the same (counter-clockwise) direction. This also helps in avoiding setting-up molecular stresses in the wire which would cause it to roll and, further, prolongs the life of the circular set which the wire acquires in being run over the setting-roller or rod R. Another roll-preventing precaution which I observe in winding the wire upon the telegraphone-reel 1 is to make sure that the wire approaches this reel in substantially the same plane as the one in which it is to be received on the said reel. (Since modern telegraphone-reels are usually very narrow, reel 1 may be considered to comprise but a single plane, in which case the wire may be said to leave the guide roller G² "in the plane" of the reel 1.)

Instead of imparting the circular set to the magnetic-wire before it is wound upon its storage reel, I may set the wire after it has been installed upon the reeling-system in which it is to be used. Thus, as shown in Fig. 2, wherein the magnetic-wire record will be understood to be maintained under tension by oppositely biased coil springs C within the separate reels 1 and 2, I simply insert the rod R "in back" of the wire, say at a point between the driving rollers 4 and 5, and then pull the wire away from the said rollers and run it at least once, from end-to-end, around the said rod. In the drawing the temporary path of the wire around the rod R is shown in broken lines, its permanent path is indicated by arrows.

As previously set forth my invention resides, in part, in the provision of a reeling system which will not itself impart a rolling movement to the magnetic-wire record. Such a reeling system is shown in Figs. 2 and 3.

The reeling system here shown is similar in many respects to the one claimed in my copending application Ser. No. 628,295 (RCV 10337), now Patent No. 2,557,012, issued June 12, 1951, and comprises a storage reel 1 and a take-up reel 2 mounted for independent rotation, in either direction, about a common axis or shaft 3 and two driving rollers 4 and 5 which are mounted in spaced relation for rotation about separate axes or shaft 6 and 7, respectively, parallel to the reel shaft 3. The magnetic-wire record, which is here designated 9, is wound to run between the storage reel 1 and the take-up reel 2 over the driving rollers 4 and 5 in paths tangent to the reels and rollers. The driving rollers 4 and 5 are each provided with a number of grooves 4a, 4b, 4c, 5a, etc. (later described) within certain ones of which the wire is received, and with a circular flange 4f, 5f, respectively, to which a driving force is applied by a rubber-tired wheel, not here shown. The arrangement of the rollers 4, 5 and the spacing of the grooves therein is preferably such that one groove on each roller is in register with the particular reel groove to which, or from which, the wire 9 is led. Thus, in the instant case groove 4a on roller 4 is in register with, or in substantially the same plane as, the mid-plane of the "storage" reel 1, and groove 5c on roller 5 is in register with the mid-plane of the groove in the "take-up" reel 2. The spacing between the rollers per se should be wide enough to accommodate the sound-head 11 (which, as shown in Fig. 4, may

be similar to the one described in copending application Ser. No. 591,071 to Henry E. Roys, RCV 9965, now Patent No. 2,469,444, issued May 10, 1949). The spacing between the rollers and the reels will ordinarily be determined by the space available in the casing or other housing in which the reel assembly is contained.

The reeling system, above described, differs from the ones shown in my above identified earlier filed case in two respects (a) in the instant case the direction of curvature of the path of the wire is uniform throughout the reeling system and (b) in the shape of the grooves 4a, 5a, etc. in the driving rollers 4 and 5.

The first mentioned feature (a) is achieved by so placing the sound-head 11 between the rollers 4 and 5 that it faces "outwardly" whereby the wire 9 is urged outwardly and is caused to traverse an arc whose radius extends in the same direction as the radii of the other curves in the system. Thus, it will be observed upon inspection of Fig. 2 that all of the curves in the path of the wire in this reeling system are to the "right," as viewed by an observer looking in the direction in which the wire is traveling. The importance of this feature of my invention will be apparent when it is appreciated that if the circularly-set magnetic wire 9 were obliged to traverse a reverse-bend the set in the wire might become completely "ironed-out" or its radius of curvature increased beyond the limits, herein-after prescribed. (In my earlier filed case the pressure exerted by the sound-head 11 on the wire 9 may result in reverse-curve which, if of a very large radius of curvature would not remove a circular set.)

As indicated at "b," above, another important feature of my present invention resides in the shape of the grooves 4a, 4b, 4c, 5a, etc. in the driving rollers 4 and 5. I have found that the wire 9 is least likely to roll when, as shown in Fig. 3, the grooves have a flat bottom x and flat sides y and z which slant off each at an angle of substantially 22.5° with respect to a line or plane normal to the axis of rotation of the rollers.

It has been my experience that rolling is most likely to occur when the wire is subjected to a reciprocating movement (as in my copending application Ser. No. 697,590 RCV 11147, now Patent No. 2,526,051 issued October 17, 1950), or is caused to set-up (or down) from a groove in one roller to a higher (or lower) groove in another roller and that the tendency of the wire to roll is most pronounced when the grooves have parallel sides and a curved bottom. In this latter connection I have observed that when a wire enters a round-bottomed groove at an angle with respect to the plane of the groove it does not ride on the center line of the groove but off-center above the bottom of the groove. As the wire advances in a round-bottomed groove it rolls downwardly and inwardly to assume a position on the center line of the groove, from whence it passes to the next roller or reel. By making the bottom of the grooves flat as indicated at x (Fig. 3), instead of curved, it becomes immaterial what position the wire occupies in the groove, since all points on the flat bottom are equally distant from the axis of the roller. As a result the wire will not roll, irrespective of the position at which the wire enters or leaves the flat-bottom x of the groove.

I have also found that a V-shape groove when perfectly clean will tend to prevent rolling but I

do not recommend the use of such grooves in magnetic-wire recorders because dust and dirt accumulate in the bottom of the V and introduce eccentricities which give rise to a jerking movement. Furthermore, any irregularities in the surface of the wire or of the groove, due to wear, may cause the wire to shift its position with respect to the axis of rotation of the roller.

The flat outwardly-inclined side walls y and z of the flat-bottomed grooves in the rollers 4 and 5 are designed to present the largest possible radius (r Fig. 3) of curvature to the wire 9 upon entering the rollers at a small angle. The 22.5° slant of these surfaces y and z is the optimum degree of slant when the diameter of the rollers 4 and 5 is substantially one inch, and the angle at which the wire enters the groove is substantially no greater than 5°. Larger rollers, or an angle of approach greater than 5°, will dictate a slant of more than 22.5° (but ordinarily not more than 45°) for the side walls y and z of the said grooves.

While, as above indicated, the tendency of the magnetic-wire to roll is greatly decreased by the use of flat-bottomed roller-grooves I rely upon the circular set of the wire to eliminate rolling. The radius of curvature of the circular set dictated by my invention is by no means critical. However, in determining the radius of curvature of the circular set with which a particular magnetic-wire record is to be endowed, the following general rules must be observed. First, the radius of curvature of the "set" should be no smaller than the radius of curvature of the smallest curve about which that particular (e. g. solid or plated iron) magnetic-wire can run without loosing its magnetism. Since it can be assumed that even the most compact telephone reeling-system will not contain such a curve, this first rule, in practice, means that the radius of curvature of the circular set should be no smaller than the radius of curvature of the smallest radius of curvature of the largest reel, roller, or pulley, in the reeling system. (In this connection I note that reeling system for iron-coated brass wire may contain smaller curves than those designed to handle solid-iron wire.)

With the foregoing parameters in mind and having regard to the elastic limit (or limits) of the wire I find it desirable to provide the wire, originally, with a circular set of a radius of curvature substantially mid-way between the radii of curvature of the smallest roller and the largest reel of the system, so that the stresses to which the wire is subjected are about equal in traversing both curves. As a practical matter a circular set of a satisfactory radius of curvature can usually be achieved by running the wire once around a 0.25 inch roller or rod (R, Figs. 1 and 2) under very slight tension. The magnetic properties of the wire are not permanently affected by running the wire around such a small curve since the circular set which the wire actually acquires in being run there around is of a radius of curvature larger than that of the said small curve.

The advantages of my invention are manifest in so-called longitudinally-magnetized wire-systems by the highly constant acoustic fidelity of the recordings. Thus, whereas "longitudinal" recordings made on various present-day wire recorders of a musical note of fixed frequency (in this case 4000 cycles per second) exhibited a variation of from 6 to 12 decibels, the same note recorded in accordance with my present invention exhibited a variation of but one-half decibel, or even less. I attribute this improved performance to the fact

that when a high-frequency audio signal is impressed, longitudinally, upon a wire record, as shown in Fig. 4, the magnetic lines of force $n-s$ may embrace less than all of the circumferential surface of the wire 9 between the pole-pieces p, p' of the applicator or sound head 11. Thus, when the record 9 is played back in a machine where the "longitudinally-magnetized" wire may roll, a different and perhaps totally unmagnetized surface section of the wire may be presented to the pole pieces of the pick-up device. (I intend the term "longitudinally-magnetized wire" as used herein to include any magnetic-recording wherein the magnetic lines of force extend, generally, along the axis of the wire, though a "transverse" component may be present, for example as in the "obliquely magnetized" wire-records of Pederson and Paulson U. S. P. 873,078.)

The substantially complete absence of rolling permits me to impress the signal energy upon a wire record in the "transverse" direction and thus to achieve the low recording and play-back speeds heretofore practical only with transversely-magnetized tape-records. In this case, referring now to Fig. 5 I mount the magnetic-pole pieces N and S of the applicator or sound-head on opposite sides of the wire 9 along a common axis normal to the direction of movement of the wire.

I claim as my invention:

A telephone comprising, in combination, a reeling system including a storage reel and a take-up reel, said reels being the opposite ends of a path along which a flexible magnetic-wire record is adapted to run, a sound head, a first guide roller intermediate said storage reel and said sound head, a second guide roller intermediate said take-up reel and said sound head, said rollers being substantially one inch in diameter, and a flexible magnetic wire record wound to run between said reels around said rollers along said path, said wire record having a preformed circular set of a radius of curvature smaller than the largest radius of curvature of either of said reels but larger than that which would effect demagnetization of said wire when previously magnetized, the curves in said path being all in the same direction of movement of said wire, each of said rollers having a wire receiving groove the bottom of which is flat and parallel to the axis of rotation of said roller and the side walls of which are flat and slant at an angle of approximately 22.5 degrees with respect to a plane normal to said axis, said wire moving along said path at points in proximity to each of said rollers at a small angle to said plane, said small angle being not more than five degrees.

TERRY M. SHRADER.
